UNITED STATES PATENT OFFICE

92,590

DESIGN FOR A PORTABLE ELECTRIC DRILL

Alonzo G. Decker, Towson, Md., assignor to The
Black & Decker Manufacturing Company,
Towson, Md., a corporation of Maryland

Application March 15, 1934, Serial No. 51,054

Term of patent 3½ years

To all whom it may concern:

Be it known that I, ALONZO G. DECKER, a citizen of the United States of America, residing in Towson, county of Baltimore, State of Maryland, have invented a new, original, and ornamental Design for a Portable Electric Drill, of which the following is a specification, reference being had to the accompanying drawing, forming part thereof.

In the drawing the figure is a perspective view of the casing looking at the same from the side.

Referring to the drawing, the body 1 of the casing is of polygonal cross section closely approaching a circular outline and has a gradual taper toward the rear from a zone 2 of greatest diameter which is near the front. Forward of the zone 2 of greatest diameter, the casing has an abrupt taper toward the nose 3 which is eccentrically located being above the center in the

position of the tool as illustrated. The handle 4 which is the dominant feature of the design is of the spade type being located at the rear and having its top arm 5 continuous with the top horizon of the body portion of the casing. The grip portion 6 of the handle extends downwardly from said top arm, being inclined downwardly and rearwardly in its relation to a transverse line at right angles to the axis of the tool, and the bottom arm 7 of the handle which joins the lower end of grip to the body is sharply inclined downwardly and rearwardly from the bottom horizon line of the body portion.

I claim:

The ornamental design for a portable electric drill as shown and described.

Signed by me at Baltimore, Maryland, this 12 day of March, 1934.

ALONZO G. DECKER.
